UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,246,881.

Specification of Letters Patent.

Patented Nov. 20, 1917.

Application filed December 21, 1916. Serial No. 138,170.

To all whom it may concern:

Be it known that I, HENRY P. CLAUSEN, a citizen of the United States, residing at Mount Vernon, in the county of Westchester 5 and State of New York, have invented certain new and useful Improvements in Telephone-Exchange Systems, of which the following is a full, clear, concise, and exact description.

10 This invention relates to telephone exchange systems and more particularly to systems of great capacity in which a connection may be established through the operation of an impulse transmitter.

15 The engineering profession has heretofore considered telephone exchange systems utilizing automatic switches impractical for use in large cities or in localities where service must be supplied to a large number of sub-

20 scribers. The difficulty encountered has been, in a sense, psychological and due to the well-established fact that very few persons are able to accurately remember a telephone number consisting of more than five digits.

25 The object of this invention is to provide means whereby a very large number of subscribers may be served through an automatic telephone exchange system, without the use of unreasonably long call-numbers, 30 or more specifically through the use of easily remembered call-numbers.

In a system serving millions of subscribers through manually operated exchanges any one subscriber may be called by another 35 through the use of a call-number which is almost in the nature of a formula, such, for instance, as "New York city, Riverside five one three four, party J", this being due to the use of the decimal system of designating 40 telephone numbers.

In a system embodying this invention any one of several million subscribers may be called through the use of a short and easily remembered call-number, such, for instance, 45 as "Red, three A, B, four."

A feature of the invention is the use of other than the decimal system in an arrangement of call-numbers and apparatus. In addition to the usual ten number digits, 50 other symbols such as letters of the Roman alphabet, letters of the Greek alphabet or monosyllabic words may be used as digits, any combination of which will represent a particular subscriber.

55 Another feature of the invention is the

provision of means whereby the subscriber in operating his impulse transmitter will not be compelled to wait an unreasonable length of time between successive operations. This may be accomplished in several ways, for 60 instance, by the sending of a code impulse or by the sending of short impulses of different characters, such as current of different frequencies, or by making all trains of impulses of uniform character, except 65 those representing the last digit, of short numbers of impulses.

Through the use of a system of code impulses, an impulse transmitter may be caused to operate at a greatly increased speed over 70 that used at present, and the impulses recorded on a register in any well-known manner, such, for instance, as that disclosed in the application of James L. McQuarrie, Serial No. 131,455, filed November 15, 1916. 75

Through the use of short impulses of currents of different frequencies, the sending of impulses representing one of a large number of digital characters will take the same time as the sending of any other one. Here 80 also the impulses may be recorded on a register which, in turn, will direct the setting of the various selectors and connectors.

Through the use of the third scheme, an impulse transmitter may be arranged to send 85 more than the usual number of trains of impulses. All the digital characters of a call-number except the last would be selected from the first ten positions, and the last only would be composed of a greater 90 number of impulses than ten. Thus, if twenty positions were provided on the impulse sender and the call-numbers were limited to four digits, the first, second, and third might be selected in any one of ten 95 different ways, and the fourth might be selected in any one of twenty ways, thus giving a capacity of 20,000 lines, or double the amount possible with the ordinary ten-position impulse sender.

Another feature of the invention is the provision for dividing the subscribers into two general classes, the preferred subscribers who receive a great number of calls, and the common subscribers who receive a comparatively small number of calls, and assigning to the first class certain easily-remembered call-numbers or designations. This is an improvement on the present-day practice, where certain large firms are assigned pre- 110

ferred designations such as 3500, pronounced "three, five, hundred," and the less regularly called subscribers are assigned a less preferable designation, such, for instance, as 5 7797, pronounced "seven, seven, nine, seven."

According to this feature, the automatic switches are made responsive to the trains of impulses representing the digits to extend a connection from a first selector to a second 10 selector or from a second selector to a third selector in the usual manner. They are arranged, however, to be responsive to the trains of impulses representing the digital characters other than the digits to extend a 15 connection in a different manner, that is, from a first selector to a third selector or from a second selector directly to a connector switch, thus eliminating a selector normally used in the establishment of a connection. 20

With the use of a designation including digital characters other than the digits and an arrangement of apparatus contemplated by this invention, a smaller number of selectors is used in setting up a connection to a preferred subscriber, while the usual number is used in setting up a connection to a common subscriber. Thus the preferred subscriber's service is quickened and, therefore, enhanced in value. 25

While this invention admits of the use of dial switches of any capacity, and selector and connector switches of corresponding capacity, it may best be exemplified by the following assumptions: 30

A system will be described in which a twenty-position dial switch may be used. The first ten positions may be designated by the ten digits, and the second ten may be 35 designated by ten digital characters which may, as before stated, be either letters of the Roman alphabet, letters of the Greek alphabet or even short easily pronounced monosyllabic words. There may even be a double designation on the dials, that is, the name of an exchange may be set opposite a character so that the train of impulses representing a certain character may also represent a certain exchange. Thus we might have 40 twenty different exchange districts designated by twenty different names, such for instance, as "Worth, Main, East, Blue, Brown or John."

It will also be assumed that the automatic 45 selector switches shall each be capable of making a selection in twenty different ways, that is, there shall be twenty vertical steps and a sufficient number of rotary steps. The connector switches may make a selection in 50 a vertical direction in twenty ways, and a selection in a rotary direction in twenty ways. Thus the capacity of the latter shall be four hundred lines, and the capacity of the exchange shall be a function of the number of selector switches used. 55

If it be now assumed that no telephone number shall consist of more than five digits, it will be seen that the system is capable of serving twenty to the fifth power, or three million, two hundred thousand subscribers. 76

It should be noted that with the decimal system used hereinbefore, the ultimate capacity of an exchange where the call numbers are limited to five digits has been ten to the fifth power or one hundred thousand. 75 Thus, by an increase of one hundred per cent. in the capacity of the impulse transmitters, an increase has been gained in the ultimate capacity of the system of three thousand, two hundred per cent. 80

In the drawings, Figure 1 is a diagrammatic representation of the arrangement of the switching mechanisms in a large non-numerical system; Fig. 2 is a detailed representation of the same; and Fig. 3 is a detailed representation of a modification of the same arranged for a division of service into two or more classes. 85

Referring now especially to Fig. 1, the figures designated LF^1 and so forth represent groups of line finder switches multiplied through cables 1, 2, 3 and so forth, to the connector switches C^1 , C^2 , and so forth. FS^1 , SS^1 , TS^1 represent respectively first selectors, second selectors and third selectors. 95

Each connector switch, since it must be capable of making twenty selections in both rotary and vertical movements, will have a capacity of four hundred lines, and on a ten percent. basis, C^1 will represent a bank of forty connector switches. Similarly, LF^1 will represent a bank of forty line finder switches. 100

LF^1 to LF^{10} are banks of line finder switches constituting a major group serving one hundred and sixty thousand subscribers' lines, there being twenty of such major groups. They may be entered by the sending of impulses corresponding to twenty exchange names, though it does not follow 110 that they should be segregated in twenty exchange buildings. Each major group then comprises four hundred such groups as LF^1 , and is in turn divided into twenty minor groups, as represented by LF^1 to LF^5 in one 115 case and LF^6 to LF^{10} in another case, each of which minor groups in turn comprises twenty such groups as LF^1 .

A subscriber having access to the system through the group LF^1 will, upon initiating a call, be served by a bank of first selectors represented by FS^1 . By then manipulating his dial switch, the subscriber may gain access to any one of the major groups of one hundred and sixty thousand subscribers' 120 lines by setting the first selector on the group of terminals leading to such major group. Assuming that the first of the twenty major groups is selected, the connection may be traced over the line 11 representing the 130

trunks leading from FS¹ to each of the major groups, then over the line 12 which represents the particular group of trunks leading to the second selector SS¹ of the first 5 major group, SS¹ to SS¹⁰ represent part of the twenty groups of second selectors into which the minor group is divided.

- The second manipulation of the subscriber's dial switch results in the selection of 10 one of twenty groups of third selectors. It will be assumed that this selection leads to the third selectors TS⁶, the connection therewith being traced over the representations of trunk cables 13 and 14.
- 15 The third selection made by the subscriber extends the connection through trunk cable 15 and, we will assume, through the particular conductors thereof represented by 16 to the group of connector 20 switches C⁸.

The last two movements of the dial switch result in the extension of the connection within the group C⁸ to terminals of the particular line wanted.

- 25 Referring now especially to Fig. 2; LF¹¹, LF¹², LF¹³ and LF¹⁴ represent banks of line finder switches, in the same manner as LF¹ in Fig. 1. FS¹¹, SS¹¹ and TS¹¹ represent respectively first selectors, second selectors 30 and third selectors, in a manner also similar to that in Fig. 1. C¹¹, C¹², C¹³ and C¹⁴ represent banks of connector switches, and the line 17 represents the cable carrying the 35 multiple conductors of lines terminating in the line finder switches LF¹¹, and so forth, and the connector switches C¹¹, and so forth.

- A line entering the system in, say, line 40 finder LF¹¹ is switched to a first selector over one of the sets of conductors included in the cable 18. If now the dial switch at the substation is manipulated in a position 45 designated by a digit, one of the first groups of levels indicated will be selected, and if it is manipulated in one of the positions 50 designated by a character not a digit, it will be set on a line terminal in one of the upper sets of levels indicated. In either case the connection will be extended to the second selector. The next set of impulses will cause one of the second selectors represented 55 by SS¹ to be set on the terminals of a line leading to a particular one of the group of third selectors represented by TS¹¹. From the third selector, any one of the connectors 60 represented by one of the group C¹¹ to C¹³ is selected, and within this connector the particular line wanted is picked out.

- Referring now especially to Fig. 3, this 65 represents a modification of the above and shows means whereby a divided service may be rendered subscribers.

- Let it be assumed that the subscriber 70 whose line enters the telephone system through the group of line finders LF¹⁵ is set upon one of the first selectors FS¹². Let

it be further assumed that the designation of the called telephone line in this case is three, A, four, six.

The sending of impulses representing the character 3 will then selectively set the first 70 selector FS¹² on one of the lower levels in the selector FS¹², thus picking out the terminals, of a second selector in the group represented by SS¹². The next series of impulses will represent the character A, and 75 the sending of these impulses will result in the setting of the second selector on a level in the upper group of levels indicated. The result of such a setting extends the connection past the third selector TS¹², directly 80 into one of the connector switches C¹⁵, C¹⁶ or C¹⁷.

The manipulation of the dial in the last 85 two digital positions results in the selection of the particular line wanted.

If it had been assumed that a designation composed entirely of digits had been selected, then the line entering the group of line finders LF¹⁵ would, in each case, have set the selector switches on one of the first 90 group of levels of each switch in turn, and the third selector TS¹² would have been included in such connection.

Let it be assumed, as another example, that a call for a prominent subscriber, or 95 one to whom preferred service is supplied, is now initiated. Such a subscriber might have a telephone designation such for instance as BF. The action of the line finder LF¹⁵ results in the extension of the calling 100 line to the first selector FS¹², and this first selector, in responding to the train of impulses representing the character B, would set its brushes on terminals in the upper group of levels indicated, thereby selecting 105 an idle third selector over the trunk cable 20. An idle third selector being selected, the impulses representing the character F would now be sent, and would result in the setting of the brushes of TS¹² on one of the 110 upper levels indicated in that group. Service of this nature is to be given only to users of a great volume, or in other words, to subscribers whose service demands a plurality of trunks. The third selector TS¹² 115 being set on one of the upper levels, will now be impelled to act in the same way as if a connector switch were to be selected, that is, after the particular level has been picked out, then an idle trunk in that level 120 must be selected. In this case all trunks in one level lead to the same subscriber, and the action will be the same as if an idle connector switch were being hunted.

What is claimed is:

1. In a telephone exchange system, lines arranged in numerical order accessible to calling lines by a plurality of groups of paths, less in number than the number of lines, selector switches adapted to select a 130

- path by means of successive selections, the number of which is determined by the number of characters in the designation of the line to which such path is to be established,
- 5 such selectors having access to more than ten groups of paths, whereby certain paths may be established by a number of selections less than the number of digits in the numerical designation of the line to which such path extends.
2. In a telephone exchange system, lines arranged in numerical order accessible to calling lines by composite paths composed of a number of component paths arranged in 15 groups, groups of component paths individual to each character of the maximum number of characters employed to represent such lines, groups of component paths individual to groups of more than one character 20 of such maximum number, selector switches adapted to select and interconnect successive paths in groups of either character in a single selective operation whereby a composite path may be established to certain lines 25 including component paths of a group of paths individual to a group of characters by a less number of selective operations than other component paths or groups of paths individual to a character.
3. In a telephone exchange system, lines arranged in numerical order accessible to calling lines by a plurality of composite paths including certain component paths arranged in decimal groups and other component paths arranged in other non-decimal groups, less in number than such decimal groups, selector switches for establishing such composite paths by successive selections depending in number upon the number of 40 groups of such component paths, and means in such selector switches rendering both decimal and non-decimal groups of component paths accessible therein, whereby certain composite paths including component paths of the non-decimal groups may be established by means of a less number of selections than by composite paths including only component paths in the decimal groups.
4. In a telephone system, lines arranged 50 in numerical order but designated on a non-decimal basis, said lines being accessible to calling lines by a plurality of groups of paths, less in number than the number of lines, selector switches arranged to select a 55 path by means of successive selection, the number of which is determined by the number of characters in the designation of the line to which such path is to be established, such selectors having access to a plurality of 60 groups of paths whereby certain paths may

be established by a number of selections less than the number of digits in the numerical designation of the line to which such path extends.

5. In a telephone system, lines arranged 65 in numerical order on a non-decimal basis, said lines being designated for purpose of calling by digits, and characters representing numbers consisting of more than one digit, whereby certain of said lines contain in 70 their designation a less number of characters than is necessary to distinguish them in their numerical order.

6. In a telephone exchange system, lines arranged in non-decimal numerical order accessible to calling lines by compound paths composed of a number of simple paths arranged in groups, groups of simple paths individual to each character of the maximum number of characters employed to represent 80 such lines, groups of simple paths individual to groups of more than one character of such maximum number, selector switches adapted to select and interconnect successive paths in groups of either character, whereby a composite path may be established to certain lines including simple paths of a group of paths individual to a group of characters by a less number of selective operations than other simple paths or groups of paths individual to a character. 90

7. In a telephone exchange system, telephone lines, means including automatic switches for interconnecting said lines, said switches being responsive to trains of impulses designated by digit to extend a connection over a path to a switch next in order and being also responsive to the trains of impulses designated by characters representing a combination of digits to extend a connection past a switch next in order to a switch second in order. 95

8. In a telephone system, telephone lines, means including automatic switches for interconnecting said lines, said switches being arranged in the order of first selectors, second selectors, and so on, said switches being responsive to trains of impulses designated by one group of characters to extend a connection over a path leading to a selector 105 switch next in order and being also responsive to trains of impulses designated by another group of characters to extend a connection past a selector switch next in order to a switch second in order. 110

In witness whereof, I hereunto subscribe my name this 19th day of December A. D., 1916.

HENRY P. CLAUSEN.
